UNITED STATES PATENT OFFICE

1,932,113

PIPE WRENCH

John R. Long, Los Angeles, Calif.

Application February 15, 1933. Serial No. 656,836

4 Claims. (Cl. 81—108)

This invention relates to an improved pipe wrench having as one of its objects improved means whereby the wrench can be more easily adjusted and applied to and thereafter used and removed from a pipe or other object. More particularly my improvement provides a comparatively stationary jaw shank upon which a movable jaw is tiltingly associated, the tilting member being out of contact with the stationary jaw member leaving the latter free to be revolved and adjusted when not applied without binding effort between said parts. My improvement also provides a structure having maximum strength, rigidity and simplicity, coupled with a minimum of material. Another object is the production of a wrench which can more easily and quickly be set for use when applied to any predetermined size of pipe or other object.

With these and other objects in view, my invention comprises the features of construction and combination of parts hereinafter described and claimed.

In the accompanying drawing, forming part of this specification, Figure 1 is a side elevation of my invention, part of the handle being broken away; Fig. 2 is a central longitudinal section of the structure shown in Fig. 1, part of the structure being shown in full side elevation; Fig. 3 is a plan of the structure shown in Fig. 1, and Fig. 4 is an end view of the rotary jaw face.

In the drawing, A indicates the handle of my improved wrench which comprises a shaft having one end thereof screw threaded at 10 and provided with a circular tip C, the circular end surface being serrated at 11 and forming a stationary abutment jaw. Said jaw C is fixed upon one end of the handle member by a pin 12. A sleeve E is adjustably engaged for longitudinal movement over the threads on said handle bar and is formed with a pair of spaced flanges F on its side extending forwardly and between which a companion pipe engaging tilting jaw member G, opposite the fixed jaw member is hinged by the pintle H passing transversely through the flanges and body of the tilting jaw. Normally the movable jaw member G is tilted towards the fixed jaw by the helical compression spring I, which is interposed between the heel of the tilting jaw and the body of the sleeve and permits tilting play of the movable jaw. Said spring is seated freely in a recess 13 in the face of the heel portion of the tilting jaw member G and the passage 14 corresponding with said recess through the sleeve E and a bearing tip 15 freely movable in said passage 14 slidably bears against

the threaded surface of the fixed jaw handle member A. A pin 16 extends upwardly from the bearing tip freely into the coil spring I. Thus the spring acts freely to more effectively perform its function during the entire tilting movement of the tilting jaw member. The bearing tip frictionally engages the handle member, thus tending to prevent the sleeve from turning on the handle member when the wrench is applied for use.

For facilitating the application of the wrench to a pipe or other object a lever J is provided on the heel portion of the tilting jaw member G integral with and extending along the handle A by which the pivoted jaw can be tilted into maximum open position. The rearward end of the lever is knurled on its outer surface at 17 so as to prevent slipping of the thumb or hand of the user when tilting the jaw member open. The jaw member G is provided with a shoulder 18 radially disposed from the axis of the pintle H and acting as a swinging stop against the inner end of the sleeve E to define the normal inward tilting or closed movement of jaw member G. The tilting movement of jaw member G is sufficient to permit the fixed and tilting jaw members being easily applied to a pipe K or other object so that when the wrench is turned in the direction of the arrow shown in Fig. 2, the jaws will firmly bite into and engage the surface to which the wrench is applied.

In use the wrench is opened to the desired size and adjusted to a pipe or other object to be turned or held in the usual way except that the stationary member is adjusted by turning handle member A to the desired predetermined position according to the diameter or size of the pipe or other object to which the wrench is to be applied, and that the jaw member G is first tilted into wide open position by depressing lever J and then released. The hand operated lever J is important in releasing the jaws from the pipe or applying it thereon. To facilitate setting the jaws in the most effective work engaging position the rotary handle member A is provided with a graduated scale L on its surface which in effect provides co-action with the screw action of the handle A and the stationary position of the sleeve E provides a micrometer adjustment by the use of which the jaws of the wrench can be set at any predetermined open size to enable ready and effective application of the wrench to its work.

It is important as is proven by experience that the jaw member C may be made to turn with the handle A and not swivel thereon. By mount-

ing the jaw in fixed relation to the handle the jaw becomes locked instantly when the wrench is used whereas if swiveled the slight turning of the handle will loosen the wrench from its work which is detrimental. The use of the hand operable lever J is important as it enables more ready releasing of the jaws from the pipe or other object. The yoke sleeve it will be noted engages the threads 10 near the jaws and extends rearwardly 10 a comparatively long distance beyond the threads where it has a second even and smooth bearing upon the shank or barrel of the handle. This double bearing at widely separated longitudinal points tends to prevent the handle from bending 15 where the threads are located while under severe strain which is a distinct advantage. The tilting jaw shank rests at a single point by shoulder 18 against the end of the sleeve E and thus reduces friction against the turning movement of 20 the handle when the latter is adjusted which is an advantage. The improved structure also tends to increase strength with a minimum of material and resulting cost of production which is also an advantage.

25 Modifications of the specific construction shown are contemplated within the spirit of the invention and within the scope of the following claims.

Having described my invention, what I claim as new and desire to secure by Letters Patent is:

30 1. A wrench, comprising, in combination, a handle bar member comprising a rotatable shaft having a screw threaded end and a tip rigidly mounted thereon forming a fixed abutment jaw, a sleeve engaged at one end by said threaded end and journaled freely at its opposite end on said handle bar, said sleeve being adjustable on said handle bar and having a pair of longitudinal flanges on its side and a transverse passage over the threaded portion of said handle bar, a forwardly extending movable jaw member opposed to said fixed abutment jaw hinged upon said flanges and having a rearwardly extending lever and a recess in the face of said lever adjacent to said sleeve, a helical spring between said lever and sleeve and seated in said recess and by which the movable jaw member is urged to tilt towards 105 said fixed jaw, and an antifriction tip freely seated in said spring and transverse passage between said spring and the screw threaded surface of said handle bar member, adapted to retard the sleeve from turning on said handle bar.

40 2. A wrench, comprising, in combination, a handle bar member comprising a rotatable shaft having a screw threaded end formed with a stationary jaw surface, a sleeve engaged at one end by said threaded end and journaled freely by its opposite end on said handle bar at a point remotely distanced from said threaded end, said sleeve being adjustable on said handle bar and 45 having a pair of longitudinal flanges on its side,

a forwardly extending movable jaw member opposed to said fixed jaw member hinged upon said flanges and having a rearwardly extending lever by the depression of which towards said sleeve said movable jaw member is tilted apart from said fixed jaw, and a spring between said lever and handle member having an antifriction tip projecting through said sleeve and bearing against the threads of said handle to retard the sleeve from turning on the handle bar.

45 3. A wrench, comprising, in combination, a handle bar member comprising a rotatable shaft having a screw threaded end and a tip on said end forming a fixed abutment jaw, a sleeve engaged at one end over said threaded end and journaled freely at its opposite end on said handle bar, said sleeve being adjustable on said handle bar and having a pair of longitudinal flanges on its side and a transverse passage over the threaded portion of said handle bar, a forwardly extending tilting jaw member opposed to said fixed abutment jaw hinged upon said flanges and having a rearwardly extending lever, a stop shoulder adapted to strike the end of said sleeve to limit the inward swinging movement of said tilting 100 jaw member and a recess in the face of said lever coinciding with said transverse passage through said sleeve, a helical spring between said lever and sleeve and seated in said recess and by which the movable jaw member is urged to tilt towards 105 said fixed jaw, and an antifriction tip freely seated in said spring and transverse passage between said spring and the screw threaded surface of said handle bar member, adapted to retard the sleeve from turning on said handle bar.

50 4. A wrench, comprising, in combination, a handle bar member comprising a rotatable shaft having a screw threaded end and a tip forming a fixed abutment jaw, a sleeve engaged at one end over said threaded end and journaled freely at 115 its opposite end on said handle bar, said sleeve being adjustable on said handle bar and having a pair of longitudinal flanges on its side, a forwardly extending movable jaw member opposed to said fixed abutment jaw hinged upon said 120 flanges and having a rearwardly extending lever by the depression of which towards said sleeve said movable jaw member is tilted apart from said fixed abutment jaw, a graduated scale dividing the side of said handle bar into measured 125 spaces adapted to coincide with the end of said sleeve to provide accurate adjustment of said jaws apart when said handle bar is revolved in said sleeve, and a spring below said lever and pressing against said rotative handle bar, tending to 130 urge the hinged jaw inwardly towards said fixed jaw and to retard rotative movement of said handle bar, whereby the jaws are held precisely adjusted in any desired open position.
